UNITED STATES PATENT OFFICE.

PHILIP A. DESLAURIERS, OF ST. PAUL, MINNESOTA.

DESIGN FOR A SIDING-PLATE.

SPECIFICATION forming part of Design No. 22,297, dated March 14, 1893.

Application filed May 5, 1892. Serial No. 431,969. Term of patent 14 years.

To all whom it may concern:

Be it known that I, PHILIP A. DESLAURIERS, a citizen of the United States, residing at St. Paul, Ramsey county, Minnesota, have invented and produced a new and original Design for a Siding-Plate for Sheet-Metal Building-Fronts, of which the following is a specification, reference being had to the accompanying drawings, illustrating the same.

10 The drawings in Figure 1 represent a plan view of my design and in Fig. 2 a cross section of the design which consists of a sheet metal plate having a substantially plane or flat surface 1 forming a border, and a portion 15 2 lying inside said border portion and extending substantially parallel with the border portion but in a different plane and connected

with the inner edge 3 of the flat border portion by an intermediate portion whereby the plate is given a recessed surface on one side ¹⁰ and a depressed surface on the other side both surfaces being in a higher plane than the flat surface 1, the portion between the border surface 1 being ornamented in imitation of picked stone. ²⁵

What I claim is—

The design for a siding plate for a building front shown and described.

In testimony whereof I have hereunto set my hand this 22d day of April, 1892.

PHILIP A. DESLAURIERS.

In presence of—

T. D. MERWIN,
H. S. JOHNSON.
